UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM AND METHOD OF OPERATING THE SAME.

Application filed January 24, 1918, Serial No. 213,523. Renewed August 7, 1923.

To all whom it may concern:

Be it known that I, EDGAR D. JOHNSON, a citizen of the United States, residing at East Orange, in the county of Essex and State of New Jersey, have invented certain new and useful Improvements in Signaling Systems and Methods of Operating the Same, of which the following is a full, clear, concise, and exact description.

10 This invention relates to electric circuits in which a repeater or the like is connected between two transmission lines in one manner for transmission in one direction, and in another manner for transmission in the 15 opposite direction.

An object of the invention is to adapt one or more one-way repeating elements for the transmission of current in both directions between the stations.

20 This has been previously done by providing a reversing switch for the repeater which is reversed unless already properly connected, in response to current impressed on the line.

25 According to the present invention, the repeater is continually reversed, i. e., pointed in first one direction and then in the other between the lines independently of the signaling current impressed on the lines.

30 This is accomplished by a system of relays which automatically permits amplified currents to be sent first in one direction and then in the other over the line. When current is impressed at either end of the line, the one-way repeater is kept from reversing by means of a relay operated by the currents to be amplified, and remains connected to the line in such a manner as to amplify the impressed currents and allow them 40 to pass to the distant station at the opposite end of the line.

When this improved repeater system is employed for handling telephone current, it has the advantage that at the instant either subscriber stops talking, it is not necessary for the other subscriber to start talking in order to reverse the direction of the one-way telephone repeater. This means that at the instant the subscriber at one end of the 50 telephone line stops talking and the subscriber at the opposite end of the line answers him, the one-way repeater may be in a position to amplify this reply and relay it to the

other subscriber without any initial lag. In any case, the lag introduced in the transmission would only be a fraction of a second or the time required for the relays to reverse automatically, which interval may be made less than the shortest time which can be made to elapse between the instant when one subscriber stops talking and the other subscriber starts talking.

Further objects of the invention will be apparent from the following detailed description taken in connection with the drawing in which the single figure shows the invention adapted to a telephone circuit.

Referring to the drawings, the subscribers' stations A and B are shown connected together through the contacts controlled by 70 the armatures 1 and 2 of the polarized relays 3 and 4. The armatures 1 and 2 control the connections of the repeater 5 to the telephone lines 6 and 7. The repeater 5 here shown is of the mechanical type but obviously any other type of repeater may be employed.

As shown in the drawing, the circuit is in a position for amplified telephone currents to pass from line 6 to line 7 (line 6 being connected to the input side of the repeater through armature 1, and line 7 being connected to the output side of the repeater through armature 2). Normally, however, that is, when neither subscriber is talking, the circuit will only stay in the position shown in the drawing for a fraction of a second, and the next instant, due to the automatic operation of relays 3, 4, 8 and 9, the circuit will be in a position for amplified currents to pass in a direction from line 7 to line 6. This automatic operation of the relays is due to the fact that normally polarized relay 9 which controls the operation of relays 3, 4 and 8 has direct current flowing 95 from the battery 10 through one operating winding 12 of the relay, the closed contacts 14 and 22 of relays 8 and 11 respectively to ground and back to battery 10 in such a manner that relay 9 will operate. Solenoid 100 12 of relay 9 being energized, the armature 13 is attracted, which connects the battery 10 by way of armature 13 through the solenoid of relay 8. Relay 8 being energized attracts its armature 14 which deenergizes 105 solenoid 12, and also attracts armature 15.

which energizes solenoid 16 of relay 9 by way of the closed contact 22 of relay 11. The solenoid 16 being energized, the armature 13 is attracted to the position shown in the drawing which deenergizes relay 8, again completing the energizing circuit of solenoid 12, as previously described, the armature 13 continuing to be attracted first by solenoid 12 and then by solenoid 16, the oscillation of this armature continues automatically. Armature 13 in the position shown in the drawing, however, connects the battery 10 by way of lead 17 to the solenoids 18 and 19 of relays 3 and 4, which attract their armatures 1 and 2 to the positions shown in the drawings, so that line 5 is connected to the input side of the repeater, line 7 to the output side. When armature 13 assumes its alternate position however, which it does automatically, the solenoids 18 and 19 are deenergized and the solenoids 20 and 21 are energized instead from battery 10. The energization of solenoids 20 and 21 moves armatures 1 and 2 to their alternate positions in which the input side of the repeater is connected to the line 7, its output side being connected to the line 6. The automatic oscillation of the armature 13 then causes a synchronous automatic reversal of the connections of repeater 5 to the lines 6 and 7. The automatic operation of relays 3, 4, 8 and 9, pointing the repeater first in one direction and then in the other, continues as long as there are no currents passing over the line between the two subscribers' stations, and the period of operation depends upon the speed of the various relays used. Relay 11, however, which is bridged across the input side of the repeater, is responsive to the telephone currents impressed on the line to set its contact 22 into vibration, thereby sufficiently increasing the resistance in circuit with solenoid 12 or 16, as the case may be, to arrest the motion of the armature 13.

If the invention had been shown as applied to the amplification of ringing currents, then the relay 11 would respond to these ringing currents to bring about the desired change in the circuit connections. The invention is not limited to any particular form of the relay 11, which, in the circuit shown, is a voice-operated relay; and as indicating one type of relay which may be employed, reference is made to the patent to Brown 1,185,472, Telephony, May 30, 1916.

As soon as the subscriber at station A starts to talk and sends out telephone currents over the line, when the input of the one-way telephone repeater, due to the automatic operation of the circuit, is connected to the line 6 from station A, these telephone currents will operate relay 11 and open the battery circuit through one of the solenoids 45 of relay 9 and keep it open as long as tele-

phone currents are passing through the winding of relay 11. This operation of relay 11 will keep the system of relays 3, 4, 8 and 9 from operating automatically and therefore the one-way telephone repeater will remain in a position to amplify the telephone currents sent out from station A and relay them to subscriber's station B at the other end of the line. The instant the subscriber at station A stops talking the contact 22 becomes quiescent and the circuit starts to reverse automatically and is in a position to be controlled by the subscriber at either of the stations A or B. If voice current is impressed on line 6 at a time when armature 1 connects the input side of the repeater to line 7, the relay 11 will not be operated until the armature 1 subsequently connects line 6 to the input side of the repeater and to the relay 11 as well. If voice current is sent out from station B, voice current not being able to go through the repeater from its output circuit to its input circuit since the repeater is a unilateral conductor, the relay 11 will only be operated when the armature 1 connects the input side of the repeater to the line 7, the output side of the repeater then being connected to the line 6 by way of armature 2. The relay 11 is permanently connected to the input side of the repeater and when temporarily connected to the incoming line 7, the relay 11 is then operated to arrest the automatic operation of relays 3, 4, 8 and 9, allowing the repeater to transmit in a direction from line 7 to line 6 as long as relay 11 is energized due to the currents impressed on the line 7.

The description of the invention with special reference to its application in connection with voice frequencies is not to be taken as limiting its scope to uses involving such frequencies, for it is obviously adapted for application to the repeating of higher or lower frequencies. Likewise, it is understood that the invention is not limited to the details of circuit arrangement here disclosed, but is capable of embodiment in many and widely varied arrangements without departing from the spirit of the invention as defined in the appended claims.

Certain broad aspects of this invention which are not claimed herein are claimed in my application, Serial No. 213,522, Signaling systems, filed of even date herewith.

What is claimed is:

1. The combination of two lines, a repeater therebetween, and means for automatically reversing the connections of said repeater to said lines, independently of the impression on said lines of direct current and of current to be repeated.
2. The combination of two lines, a repeater therebetween, means for automatically reversing the connections of said repeater to said lines independently of the impres-

sion on said lines of current to be repeated, and means responsive to current impressed on said lines for arresting said reversal.

3. A two-way repeater system comprising two lines, a repeater therefor, a relay controlling the connections of said repeater to said lines, and means for automatically associating said relay with and disassociating said relay from said lines, independently of the impression of current to be amplified on said lines.

4. A two-way repeater system comprising two signaling lines, a repeater therefor, a relay controlling the connection of said repeater to said lines, and means for automatically operatively connecting said relay alternately to said lines.

5. A two-way repeater system comprising two lines, a repeater adapted to be connected thereto and means for controlling the repeater connections comprising a relay having an armature adapted to assume at least two different positions, a second relay controlled by and adapted to control said first relay, and connections between said relays whereby said armature is adapted to be kept in motion independently of the current to be repeated.

6. A two-way repeater system comprising two lines, a repeater adapted to be connected thereto and means for controlling the repeater connections comprising a relay having an armature adapted to assume at least two different positions, a second relay controlled by and adapted to control said first relay, connections between said relays whereby said armature is adapted to be kept in motion independently of the current to be repeated, and a third relay for arresting said motion.

7. A two-way repeater system comprising two lines, a repeater adapted to be connected thereto and means for controlling the repeater connections comprising, a relay having an armature adapted to assume at least two different positions, a second relay controlled by and adapted to control said first relay, connections between said relays whereby said armature is adapted to be kept in motion, and a reversing switch controlled by said armature.

8. A relay having an armature adapted to assume at least two different positions, a second relay controlled by and adapted to control said first relay, connections between said relays whereby said armature is adapted to be kept in motion, a third relay for arresting said motion, a reversing switch controlled by said armature, a repeater adapted to be reversed by said switch, and two lines between which said repeater is connected, said third relay being responsive to the impression on said lines of current to be repeated.

9. The combination of two lines, a re-

peater adapted to be reversibly connected therebetween, switching mechanism for controlling the repeater connection and comprising an armature connected to one side of one of said lines, an armature connected to one side of the other of said lines, a plurality of contacts for each armature, the contacts for each of said armatures being connected to the opposite sides of said repeater, and automatic means for repeatedly reversing the position of said armatures in rapid succession independently of the passage of signal current through said repeater.

10. The combination of two lines, a repeater therebetween, and means for automatically and continually reversing the connections of said repeater to said lines when no voice currents are impressed on said lines.

11. The method of operating a repeater circuit which comprises reversing the connection of the input and the output sides of said repeater in said circuit while no currents are to be repeated, and suspending the reversing operation at other times.

12. The method of operating a repeater circuit which comprises reversing said repeater for transmission alternately in opposite directions in said circuit while no current is to be repeated, applying to one end of said circuit impulses to be repeated, and maintaining the repeater in condition for transmission toward the other end of the circuit while said impulses are being applied.

13. A repeater system comprising two lines, a repeater therefor, means for reversing the connections of said repeater to said lines, continually operating means controlling said reversing means, and means responsive to current impressed on said lines for preventing said continually operating means from operating said reversing means.

14. A repeater system comprising two lines, a repeater therefor, means for reversing the connections of said repeater to said lines, means comprising a movable contact for operating said reversing means, said contact assuming a plurality of positions for reversing said repeater, means for continually moving said contact, and means for assuming control of said reversing means independently of said contact.

15. In a repeating system, a unidirectional repeater, and means for controlling the pointing of said repeater, said means comprising a switch and alternative means for operating said switch, one of said means continually operating and another of said means operating intermittently.

16. A repeating system comprising a line, a repeater therefor, means for connecting said repeater to and disconnecting said repeater from said line, a movable contact controlling said connecting and disconnecting means, means for moving said contact

- independently of current impressed on said line, and means responsive to current impressed on said line for assuming control of said connecting and disconnecting means.
- 5 17. The combination of a plurality of lines, a device to be reversibly connected therebetween, a movable contact forming the termination of one side of one of said lines, a movable contact forming the termination of one side of another of said lines, stationary contacts for each of said movable contacts, interconnections between said stationary contacts, connections from said interconnections to said device, and a relay responsive to current in each of said lines for controlling said movable contacts.
- 10 18. A two-way repeater system comprising the combination of two telephone lines, a repeater to be reversibly connected therebetween, a movable contact forming the termination of one side of one of said lines, a movable contact forming the termination of one side of another of said lines, front and back contacts for each of said movable contacts, a connection between the front contact of one set and the back contact of another, connections from said front and back contacts to said repeater, and automatic means for repeatedly reversing the position 15 of said movable contacts in rapid succession while no currents are to pass through said repeater.
- 20 19. A signalling system comprising a plurality of stationary contacts, a movable contact adapted to be cyclically connected therewith, two solenoids for actuating said movable contact, a source of electromotive force, means for connecting said source to said solenoids alternately, and means responsive to alternating currents for controlling 25 said first mentioned means.
- 25 20. A signaling system comprising a plurality of stationary contacts, a movable contact adapted to be cyclically connected therewith, motive means for driving said movable contact, and means responsive to currents within the voice frequency range for modifying the cyclical connection of said contacts.
- 30 21. A signaling system comprising a plurality of lines, connections comprising synchronously operated contacts for cyclically connecting said lines, and means responsive to alternating currents impressed on one of said lines for arresting the cyclical connection.
- 35 22. A two-way repeater system comprising two lines, a repeater, connections comprising synchronously operated contacts for cyclically reversing the repeater connections 40 while no currents are to be repeated, and means responsive to an impulse impressed on one of said lines for arresting the reversal of said repeater.
- 45 23. The method of operating contacts which comprises applying electromotive force to the contacts at times, cyclically connecting one contact with another when there is no electromotive force across the contacts and suspending the cyclical operation upon 40 the application of electromotive force to the contacts.
- 50 24. The method of operating a unidirectional repeater which comprises cyclically reversing the pointing of the repeater in the intervals during which no currents are to be repeated, applying to said repeater impulses to be repeated, and arresting the reversal of the pointing of the repeater upon 55 the application of said impulses to said repeater.
- 55 25. The method of two-way telephone current repeating which comprises cyclically connecting one contact with another in the intervals during which no currents are to be repeated, and in arresting the cyclical operation in response to telephone currents.
- 60 26. The combination of two lines, a repeater therebetween, and means for automatically reversing the connections of said repeater to said lines independently of the impression of electromotive force on said lines.
- 65 27. The combination of two lines, a repeater therebetween, and means for causing reversals of the pointing of said repeater to occur automatically in rapid succession.
- 70 28. A two-way repeating system comprising two lines, a repeater therebetween, and means for automatically reversing the connections of said repeater to said lines at a given frequency.
- 75 29. A two-way repeater system comprising two lines, a repeater therefor, a relay controlling the connection of said repeater to said lines, and means for automatically connecting said relay alternately across said lines.
- 80 30. A two-way repeater system comprising two lines, a repeater therefor, a relay coil controlling the connection of said repeater to said lines, and means for automatically connecting said relay coil alternately to said lines.
- 85 31. The combination of two lines, a repeater therebetween, means for causing reversals of the pointing of said repeater to occur automatically in rapid succession, and means for preventing reversal of the repeater when impulses are to be repeated.
- 90 32. A two-way repeating system comprising two lines, a repeater therebetween, means for automatically reversing the connections of said repeater to said lines at a given frequency, and means for preventing reversal of the repeater when impulses are to be repeated.
- 95 33. The method of controlling a unidirectional repeating element which comprises cyclically reversing the pointing of the re-

peating element at small time intervals, between times when current is to be repeated.

34. The method of controlling a repeater circuit which comprises cyclically reversing the connection of the repeater to the circuit for transmission alternately in opposite directions, between times when current is to be repeated.

35. The combination of a solenoid, a movable contact controlled thereby, a source of current for said solenoid, a movable contact for reducing the current through said solenoid to a small value, a vibratile contact controlling the action of said second mentioned contact, and a switch controlled by said first mentioned contact.

36. A signaling system comprising a line,

a repeater adapted to be reversibly connected thereto, and means for controlling the repeater connections comprising a solenoid, a movable contact controlled thereby, a source of current for said solenoid, a movable contact for reducing the current through said solenoid to a small value, a vibratile contact responsive to current impressed on said line for controlling the action of said first mentioned contact, and a switch controlled by said first mentioned movable contact for controlling the repeater connections.

In witness whereof, I hereunto subscribe my name this 18th day of January A. D., 1918.

EDGAR D. JOHNSON.
